HIGH-FREQUENCY TUBE TUNING SYSTEM

Robert Allen, Lexington, Mass., assignor to the United States of America as represented by the Secretary of the Air Force

Application October 14, 1955, Serial No. 540,659

3 Claims. (Cl. 315—5.47)

(Granted under Title 35, U. S. Code (1952), sec. 266)

The invention described herein may be manufactured and used by or for the United States Government for governmental purposes without payment to me of any royalty thereon.

The present invention relates generally to means for tuning high-frequency tubes and as illustrated herein relates more particularly to a construction which maintains diaphragms of the resonant tube cavities of such tubes in substantial parallelism throughout the tuning range.

One object of the present invention is to provide a construction by the use of which the tuning of a high-frequency tube having hollow resonators may be quickly and conveniently accomplished. To this end, the tube has clamped thereto a tuning device which is arranged to be fixed to a pair of peripheral flanges on the tube which in turn are connected to deformable diaphragms forming end walls of the hollow resonators which form a part of the evacuated envelope of the tube in such a manner that the diaphragms are maintained in symmetrical relation during the entire extent of the tuning movement.

Another object of the invention is to improve generally upon the construction and operation of devices for tuning high-frequency tubes.

Other objects and features of the invention will appear hereinafter from the following description when read with reference to the accompanying drawings which illustrate a preferred embodiment of the invention and in which:

Fig. 1 is a view, partly in section, taken along the line I—I of Fig. 2;

Fig. 2 is a sectional view taken along the line of II—II; and

Fig. 3 is a view, partly in section, taken along the line III—III of Fig. 1.

The present invention is concerned with an improved tuning device for a high-frequency tube 10 having enclosed hollow resonators and which is operable not only as a self-oscillator but may also be operated as an amplifier and detector as well.

The tube 10 as shown in the drawing is of the super high-frequency velocity modulation type having a pair of resonant cavities 12, 14 having deformable end walls 16 and 18, respectively. The end walls 16 and 18 are connected to rigid flanges 20, 22, respectively, by reduced neck portions 24 and 26, as shown in Fig. 1 of the drawing. Movement of the flanges 20 and 22 in opposite directions will impart equal movement to the end walls 16 and 18.

In order to impart proper tuning movement to the flanges 20, 22, by a tuning device 28 which is so constructed and arranged that the deformable end walls or diaphragms 16, 18 are held in symmetrical relation to each other at all times during the tuning operation, the tuning device 28 is provided with right and left housing members 30, 32, which, as best shown in Fig. 2, are secured to upper and lower supporting brackets 34, 36 which in turn are fixed to a supporting panel 38.

The Klystron tube 10 is provided with a peripheral

2

flange 40 which is clamped to a plate 42 by segments 44, 46 (Fig. 3). The plate 42 is secured to the end housing 32 by shouldered spacer posts 48, 50. As shown best in Fig. 1, the outer end of each post 48, 50 is reduced in diameter to receive a bearing 110 for a gear 104, as will later be described, and to provide shoulders 56 which serve also as abutments to limit movement of the movable tuning plates 58 and 60 toward each other. The posts 48, 50 are very carefully and accurately machined to insure that the plates 58, 60 will be absolutely parallel to each other when the plates are engaged with the shoulders or abutments 56. The posts 48, 50 are each secured to their respective end plates or housings 30, 32 by suitable machine screws 62.

15 The tuning mechanism illustrating a preferred form of the present invention comprising a tuning knob 64 affixed to one end of the shaft 66; the shaft 66 at its inner end portion (Fig. 3) being mounted in spaced bearings 68 which are formed on a supporting bracket 70 secured to the plate 42 by machine screws 72. The shaft 66 has pinned thereto a worm 74 which is located between the bearings 68 and which meshes with a worm gear 76 affixed to a shaft 78 by a suitable pin 80. The shaft 78 is held from endwise movement in one direction by a spacer member 82 which bears at one end against the hub of the worm gear 76 and its other end bears against the spur gear 84 affixed to the left hand end of the shaft 78. Endwise movement in the other direction is prevented by a sleeve 86 having its right hand end against the spur gear 84 clamped to the right hand end portion of the shaft 78, as will later be described. The sleeve 86 is held in position on the shaft 78 by a collar 89. The spur gears 84, 88 mesh with internally toothed ring gears 90, 92, respectively. The ring gears 90, 92, as shown best in Fig. 1, are rotatably supported within the end casings 30, 32. As shown, the ring gears are supported within the end casings by bearings 94, 96, which are rotatably secured to the ring gears at spaced locations by bolts 98, 102. The bearings 94, 96 engage the inner peripheral surfaces of their respective housings 30, 32. As shown, the ring gears are maintained in axial position within their respective housings by the studs or bolts 98, 102 which are of substantially the same length as the inner axial dimension of each of the housings 30, 32. With the construction just above described, the ring gears 94, 96 are free to rotate within their respective housings when the tuning knob 64 is rotated in one direction or the other. The spur gears 84, 88 are identical and the teeth thereon are precision cut, as are the internal teeth on each of the ring gears 90 and 92. Thus, back lash between the various sets of meshing gears is reduced to a minimum.

Reference heretofore has been made to plates 58, 60 which are provided with axially disposed openings to receive threaded hub portions of spur gears 104, 106. The construction and assembly of each of these spur gear units 104, 106 are substantially identical and hence it will be necessary to describe only one of these assemblies in detail.

65 Referring now to Fig. 1 of the drawing, the spur gear 104 is shown in section as having its teeth meshing with the ring gear 92. The spur gear 104 is provided with an outwardly extending shouldered portion which bears against the inner wall of the housing 32 and is provided with an inwardly extending hub portion 108 which is threaded into a threaded opening 112 formed in the plate 60. In order to reduce friction between the rotating spur gear 104 and the post 48, an anti-friction bearing 110 surrounds the reduced outer end portion of the post 48. The housing 32 is secured to the post 48 by a suitable machine screw 113. As shown in Fig. 2, there are three gears 104 which mesh with the ring gear 90. Like-

wise the plate 58 is provided with three threaded openings for receiving the threaded hub portions of the gears 106. It is to be noted that the hubs of the gears 104 and 106 are oppositely threaded so that the plates 58 and 60 will simultaneously move toward and away from each other a fixed distance depending upon the rotation of the tuning knob 64.

The plates 58 and 60 are clamped to the axially displaced flanges 20 and 22 hereinbefore referred to by means of clamping segments 114 and 116, respectively. Thus, as the plates 58 and 60 move toward and away from the other the flanges 20 and 22 will likewise move toward and away from each other, depending upon the direction of rotation of the tuning knob 64. As previously stated, the diaphragms 16, 18 are connected to the flanges 20, 22 by reduced neck portions 24 and 26 in such a manner that movement of the flanges 20 and 22 will be imparted to the deformable end walls or diaphragms 16, 18. The end walls 16 and 18 may be provided with spaced corrugations to permit deformation and displacement of the end walls 16 and 18 without danger of ultimate breakage thereof.

Reference has heretofore been made to clamping the spur gears 84, 88 which are mounted on the shaft 78. As shown most clearly in Fig. 1, the spur gear 88 at the right hand end of the shaft 78 is provided with an outwardly extended hub portion having a shoulder which is arranged to engage the inner face of the end wall of the housing 32. The hub is continued outwardly beyond the housing 32 through an opening therein and is provided with an intermediate threaded portion 120 and a beveled portion 122 which is split to permit the hub to be securely clamped to the shaft 78. A clamping nut 124 is shown as provided with a threaded portion and a beveled portion coinciding with the bevel 122 on the hub of the spur gear 88. Thus when the clamping nut 124 is threaded on to the hub of the spur gear 88, the gear 88 will be rigidly clamped to the shaft 78 by the clamping action of the coating beveled faces on the nut and on the spur gear. The left hand end of the shaft is provided with a spur gear 84 which is provided with a hub portion which is identical with the hub portion of the gear 88, as described above. During initial assembly of the parts the flanges 20 and 22 are parallel to each other by being assembled with the clamping plates 58 and 60 with the plates bearing against the shoulders of the spacer posts 48 and 50 as hereinbefore described. After the posts have been thus assembled, the clamp nut 124 is tightened to lock or clamp the spur gear 88 into locking engagement with the shaft 78. The clamping nut 126 at the left hand shaft 78 having previously been tightened to lock the gear 84 to the shaft 78, both spur gears are now fast on the shaft 78 and are rotated as a unit. Thus since the plates 58 and 60, which are rigidly connected to the flanges 20 and 22 to the deformable end walls or diaphragms 16 and 18 of the resonant tube cavities, are initially parallel they will remain parallel throughout the extent of tuning movement due to precision machining of the coating elements of the tuning mechanism.

The above description is merely illustrative and is not intended to define or limit the present invention but is for purposes of illustration only.

Having thus described my invention, what I claim as new and desire to secure by Letters Patent of the United States is:

1. A tuning device for high-frequency tubes having a pair of spaced evacuated hollow resonators and deformable walls associated with each of said resonators, said tuning device comprising means for rigidly supporting said tube, a pair of members arranged for movement toward and away from each other and each having a plurality of threaded openings, means for connecting said pair of members to the deformable ends of said tubes to impart movement to the deformable end walls of said spaced resonators, a plurality of gears threaded into said members to impart axial movement thereto and to said connecting means, a ring gear coupled to each of said members and meshing with the plurality of gears above referred to, and driving gears meshing with said ring gears and fixed to a single shaft for imparting rotary movement to said ring gears whereby said deformable end walls may be moved toward and away from each other to tune said tube.

2. A tuning device for a high-frequency tube having a pair of spaced evacuated hollow resonators and deformable walls associated with each of said resonators, said device comprising means for rigidly supporting said tube including a flat plate clamped to an intermediate portion of said tube, a pair of parallel plates arranged for movement toward and away from each other having threaded openings therein, means for connecting said last mentioned plates to said deformable walls of said hollow resonators, gears having threaded hubs entering the threaded openings in said plates, a ring gear coupled to each of said plates for rotating said gears, and means interconnecting said ring gears for moving said plates and the said deformable walls connected thereto toward and away from each other.

3. A tuning device for high-frequency tubes having a pair of spaced hollow resonators and deformable walls associated with each of said resonators, said tuning device comprising a rigid frame for supporting a tube, a pair of plates mounted in said frame and arranged for movement toward and away from each other and having threaded openings therein, means for connecting said pair of plates to said tube to impart movement to the deformable end walls of said spaced resonators, a plurality of gears having hub portions threaded into said plates to impart axial movement thereto as said gears are rotated, a separate ring gear coupled to each of said members and meshing with the plurality of gears above referred to, and driving gears fixed to a single shaft and meshing with said ring for imparting rotary movement to said ring gears whereby said deformable end walls may be moved toward and away from each other to tune said tube.
